JOINTER KNIFE SETTING GAUGE

Harold R. McCormick, Winslow, Ariz.

Application May 3, 1951, Serial No. 224,300

3 Claims. (Cl. 33—185)

1

My invention relates to a gauge for use in setting the knives or jointers, and the like.

It is exceedingly difficult to set the knives in a jointer head in absolute tangential alignment with the fixed or rear table of the jointer, and unless the knives are so set they cannot produce efficient work. In the majority of jointers or planers in use today, the task of sharpening and resetting the knives is complex and exacting, and the sequence of operations involved is roughly as follows. First, each knife is removed from the cutter head and sharpened, and the knives are then replaced in the head manually and a rough preliminary gauging of the knives is carried out during the initial tightening of the knife set screws. After this, through the use of a straight edge or other suitable gauge, the knives are gradually adjusted into proper position with relation to the rear table of the machine, by means of pressure, pounding or adjusting set screws, provided for that purpose in the cutter head. After final tightening of the knife clamping set screws, a final check with a straight edge or gauge is made to assure that the final tightening of the set screws has not caused displacement of the knives. It is frequently necessary to realign one or more knives when this final check is made.

It is a primary object of this invention to provide a highly simplified gauge device which will reduce to a single simple operation the previously discussed complex task of setting the jointer knives after sharpening them.

A further object of the invention is to provide a jointer knife setter gauge which will enable an unskilled workman to set the knives in a jointer head so that every knife and every portion of the edge of every knife will travel in a perfectly cylindrical path about the axis of the head in tangential alignment with the rear table of the jointer.

A further object is to provide a gauge device of the above-mentioned character which may be used for setting jointer knives of various lengths, widths and thicknesses.

A further object is to provide a jointer knife setter gauge which simultaneously holds the sharpened knife with a vise-like action, positions the blade properly with respect to the rear or fixed table of the jointer, and maintains this position exactly during the tightening of the knife clamping set screws in the jointer head.

A still further object of the invention is to provide a gauge device of the above-mentioned character which is highly simplified, light, sturdy and durable in construction and relatively cheap to manufacture.

2

Other objects and advantages of the invention will be apparent during the course of the following description.

In the accompanying drawings, forming a part of this application, and in which like numerals are employed to designate like parts throughout the same,

Figure 1 is a plan view of a jointer knife setting gauge embodying my invention and having a jointer knife clamped therein,

Figure 2 is a fragmentary longitudinal vertical section through a conventional jointer and illustrating a side view of the knife setting gauge as it would appear in use thereon,

Figure 3 is a central vertical longitudinal section taken on line 3—3 of Figure 1 and showing portions of the jointer, for the purpose of illustration,

Figure 4 is an end elevation of the gauge as illustrated in Figure 1, part broken away, and

Figure 5 is a fragmentary side elevation of the gauge in use with a different type jointer head.

In the drawings, where for the purpose of illustration is shown a preferred embodiment of my invention, the numeral 10 designates generally a gauge block or body, preferably formed of cast steel, or the like, and accurately ground to produce a perfectly flat bottom surface 11. The gauge block 10 has substantial thickness, as shown, so that it will be subject to no bending or deflection. The gauge block is preferably divided with a large opening 12 near its rear end to materially lighten the same and the gauge block has a large rectangular recess 13 in its forward end, as shown. The provision of the opening 12 and recess 13 forms longitudinal side bars or sections 14, rear and intermediate transverse bars 15 and 16, and forwardly extending parallel longitudinal arms 17, all integrally joined, as shown. The overall width of the gauge block 10 is preferably about three inches, and its overall length may be approximately three and one-half inches, although these dimensions may be varied as desired. The forward ends 18 of the arms 17 are beveled or inclined at an angle of approximately 30 degrees to the vertical, Figure 2, which is the knife angle of most conventional jointers. The inclination or angle of the ends 18 may, however, be varied as desired corresponding to variations in the knife angles of certain commercial machines.

A fixed transverse jaw or plate 19 extends between the arms 17 and engages the inclined ends 18, as shown. The jaw 19 is rigidly secured to the arms 17 by means of screws 20, engaging in screw threaded openings formed in the forward

ends of the arms 17. The fixed jaw or plate 19 has its lower longitudinal edge projecting below the lower face 11 of the gauge block, as shown at 21, and the edge 21 is preferably beveled or inclined with respect to the opposite faces of the jaw 19, so that it is parallel with the lower surface 11 of the gauge block. The lower beveled edge 21 forms with the inner side of the jaw 19 a sharp longitudinal corner or knife edge 22 which is maintained straight and true. The jaw 19 is preferably about an eighth of an inch thick, so as to possess a high degree of rigidity, although this thickness may be varied if desired.

A movable transverse jaw or bar 23 extends between the arms 17 and is shiftable longitudinally of these arms toward and from the fixed jaw 19. The movable jaw 23 is rectangular in transverse cross section, Figure 3, and is provided at its opposite ends with upper and lower longitudinal extensions or lugs 24 which slidably engage the upper and lower surfaces of the arms 17 for guiding the jaw 23 along the arms. The movable jaw 23 has free sliding engagement along the arms 17, but the contacting surfaces between the arms and movable jaw 23 are accurately ground and smooth so that the movable jaw 23 will not bind or deviate from its parallel relation to the fixed jaw 19. As best shown in Figure 3, the movable jaw 23 is disposed vertically and has its lower longitudinal edge 25 disposed below the lower face 11 of the gauge block, and this edge 25 forms with the forward side 26 of the movable jaw 23 a longitudinal square corner 27 which is straight and true. The lower longitudinal edge 25 of the movable jaw terminates a slight distance above the corresponding longitudinal edge 21 of the fixed jaw 19. The square longitudinal corner 27 of the movable jaw 23 is arranged in opposition to the innermost inclined surface of the fixed jaw 19, at a point just above the lower longitudinal edge 21.

The intermediate transverse bar 16 is provided at its longitudinal center and at the transverse center of the gauge bar 10 with a longitudinal screw threaded opening 28, receiving an adjusting set screw 29, which is preferably an Allen head set screw. The forward end of the adjusting set screw 29 engages the rear side of the movable jaw 23, at the longitudinal center of such jaw, as shown. When the movable jaw is shifted toward the fixed jaw 19 and into clamping engagement with the jointer knife, the set screw 29 is tightened to securely clamp the movable jaw against the knife.

In Figure 2 typical portions of a conventional jointer are shown for the purpose of illustrating the use of my gauge, and such portions include the rear or fixed table 30, with which the knives must be aligned, the front adjustable table 31, jointer shaft 32 and jointer head 33 mounted upon the shaft 32 for counterclockwise rotation therewith. The numeral 34 designates a knife holding recess or slot in the head 33, within which is adjustably mounted a jointer knife clamping block 35, actuated by jointer knife clamp screws 36, having screw threaded engagement with the head 33. The jointer knife 37 to be set engages in the recess 34 between one side wall of the same and the clamp block 35.

After each jointer knife 37 has been removed from the head 33 and sharpened, my gauge is employed to reset the knife with its sharpened edge in exact tangential alignment with the top of the rear table 30. To do this, the sharpened or beveled edge 38 of the knife 37 is brought into

contact with the bottom faces of the arms 17 and directed upwardly, as shown. The beveled face 38 is now inclined with respect to the horizontal, as shown. The forward side of the knife 37 lies flat against the inner side of the fixed jaw 19, and the movable jaw 23 is shifted toward the fixed jaw until its lower square corner 27 engages the rear side of the knife 37, just below its beveled face 38. The square corner 27 affords a firm grip on the knife 37, and the knife is now clamped securely between the fixed and movable jaws by the tightening of the adjusting screw 29. The sharpened edge of the knife 37 has bearing contact near its opposite ends with the lower ground faces of the arms 17, and this assures that the knife will be in exact alignment with the top of the table 30 throughout its entire length when set in the head 33.

The gauge block 10 is now placed in the proper position upon the rear table 30, so that the blade 37 may enter the slot 34 of the head. The knife clamping screws 36 are now tightened against the clamping block 35, while the gauge block remains flat against the table 30. The adjusting screw 29 is now loosened, and the gauge is removed, and no further adjusting or gauging of the jointer knife is required. The sharpened edge of the jointer knife 37 is now in absolute alignment throughout its entire length with the top of the table 30, and this is the necessary condition for the jointer to operate efficiently.

It can now be seen that my gauge provides for the accurate and efficient setting of jointer knives with an absolute minimum of labor and little or no skill required to perform the operation. No separate or movable gauging devices are needed, after the sharpened knives are clamped in place upon the head 33, and the setting of the knives is completed when the gauge device is removed. The device is highly simplified in construction, light weight and extremely sturdy and durable.

In Figure 5 the gauge is illustrated in use with a slightly different type of jointer including a jointer head 39 having a knife receiving slot 40 which is narrower than the slot 34. Clamping set screws 41 are provided which bear against the knife clamping block 35 to shift the same into clamping engagement with the knife 37. The set screws 41 are operated with a screw driver from the outside of the head 39. In the type of jointer illustrated in Figure 2, the slot 34 is wide enough to accommodate a wrench for the head of the clamp screw 36. In either case, it can be seen that my gauge can be used effectively for setting the jointer knives, and no parts of the gauge interfere with or develop a clearance problem with parts of the jointer.

It is to be understood that the form of the invention herewith shown and described is to be taken as a preferred example of the same, and that various changes in shape, size and arrangement of parts may be resorted to, without departing from the spirit of the invention, or the scope of the subjoined claims.

Having thus described my invention, I claim:

1. A gauge device for use in setting jointer knives comprising a block having a flat surface to rest upon a table of the jointer, the block having a recess in one end thereof forming a pair of parallel arms, the ends of the arms being beveled to an obtuse angle with respect to the flat surface of the block, a plate secured to the beveled ends of the arms and extending between the arms and having one longitudinal edge ex-

tending downwardly below said flat surface of the block to form a fixed abutment, a bar extending between the arms and slidably engaging the same for movement longitudinally thereof toward and from the fixed abutment, one longitudinal edge of the bar extending downwardly below the flat surface of the block and arranged in opposition to the fixed abutment, and an adjusting screw connected with the block and engaging the movable bar to hold the same in a selected clamping position.

2. A gauge device for use in setting jointer knives comprising a block having a flat surface to rest upon a table of the jointer, the block having a recess in one end thereof forming a pair of parallel arms, a plate secured to the ends of the arms and extending between the same and having a longitudinal edge projecting below the flat surface of the block and forming a fixed abutment, a bar extending between the arms and connected therewith for movement longitudinally thereof toward and from the fixed abutment, one longitudinal edge of the bar projecting below the flat surface of the block and arranged in opposition to the fixed abutment, and adjustable means carried by the block and engaging the bar to hold the same in a fixed position with respect to the abutment.

3. A gauge device for use in setting jointer knives comprising a block having a flat surface to slidably rest upon a table of the jointer, said block having a width corresponding generally to the length of the knife to be set, a member carried by one end of the block and projecting downwardly below the block to form an abutment

10
